[57] **CLAIM**

The ornamental design for boot shield for a motorcyclist, as shown.

DESCRIPTION

FIG. 1 is a top and left side perspective view of a boot shield for a motorcyclist, showing my new design;

FIG. 2 is a top and right side perspective view thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of a boot in FIGS. 1 and 2 is for illustrative purposes only and forms no part of the claimed design.
